WILLIAM SAUL SMITH AND FREDERIC SLAYTON WILLIAMS, OF PHILADELPHIA,
PENNSYLVANIA.

CHECK-PUNCHING DEVICE.

Application filed March 22, 1922. Serial No. 545,655.

To all whom it may concern:

Be it known that we, WILLIAM SAUL SMITH and FREDERIC S. WILLIAMS, citizens of the United States, and residents of the 5 city of Philadelphia, county of Philadelphia, State of Pennsylvania, have invented an Improvement in Check-Punching Devices, of which the following is a specification.

10 The object of our invention is to provide means adapted for perforating a bank check or its equivalent having certain limiting numbers thereon whereby certain of the numbers may be punched out for providing permanent indications of a limiting 15 character upon the check or its equivalent, the construction being effective, simple, inexpensive and convenient.

The perforating device comprises a punch 20 member, a die member, and a stripper member, the latter being of spring metal and adapted to permit the numbered end of the check to be received between it and the punch member also permitting adjustment 25 so that the number to be punched may be seen through the aperture in the die member to insure proper positioning; and the said die member and stripper member simultaneously depressed with the check or paper 30 sheet to be punched between them so as to forcibly punch out the sheet and thereafter to strip the sheet from the punch while holding it between the stripper and die member for permitting a further adjustment 35 thereof and a repetition of the punching operation.

More specifically considering the perforating means, it is adapted to be removably clamped to the cover of a bound 40 volume of checks or their equivalent and provided with spring means for gripping said cover, so that when the checks or sheets of the book have been all detached and used, the punching device itself may be detached 45 and positioned upon a duplicate book.

In the specific form of the punching device, it comprises a U shaped metal frame, one part having a punch aperture and constituting the die member, said U shaped 50 frame combined with a rigid plate secured to the die member adjacent to the bend thereof and provided with an upwardly extending punch in alinement with the hole in the die member, whereby it cooperates

for punching a hole in the paper sheet; and 55 further provided with a curved stripper plate also secured to the die member adjacent to its bend and arranged between the punch and the die member and having therein a hole for permitting the passage of 60 the punch when cooperating with the die member, the said plate carrying the punch and the plate member formed as a continuation from the bend of the die member constituting clamping jaws between which the 65 cover of the check book is received and clamped.

Our invention will be better understood by reference to the drawings, in which: Fig. 1 is a plan view of an open check book illustrating the construction of the check and its association with the perforating means; Fig. 2 is a transverse sectional view of the same, taken on line 2-2 of Fig. 1; and Fig. 3 is an enlarged view of the punch and die 75 portion of the perforating means when removed from the cover of the check book.

2 represents the cover portion of a check book and 3 illustrates a package of checks, one of which, in preferred form, is shown 80 with all of the words and markings thereon, the check being shown as attached to the stub 7 and detachable therefrom along the weakened line 8, as is customary. More particularly, it will be observed that the right 85 hand end 4 of the check contains the signature and the place for the figures designating the amount for which the check is made out, and further, the main part of the check is, as usual, comprised of the name of the 90 bank, the number of the check, the place for the name of the payee, and the line for the written designation of the amount. At the left hand end of the check is arranged a plurality of vertical rows of figures, said 95 rows each comprising figures of one denomination, respectively from 0 to 9, inclusive, as clearly shown at 22. Other designations or printed matter may be employed as indicated at 23 and 24.

100 Referring now to the punching devices 9 for perforating the numbers of the vertical rows of figures 22, the same consists of a plate bent into U form at 11 to comprise a lower member 10 and an upper punch plate 105 member 12 having therein a die aperture 14 and a forwardly projecting nose portion 13 for properly guiding the check sheet 3.

The member 12 is further provided with a depression 15 immediately back of the end 13 and aperture 14 therein, to constitute a finger receiving part for insuring proper pressure upon the punch plate. The punch plate is bent upward and is weakened at 21 by removal of part of the metal for its transverse width, so as to give more elasticity to the plate and less resistance to its 10 operation. In addition to the members 10 and 12 thus described, there is a base plate 16 having thereon an upwardly projecting punch 17 adapted to be received in the aperture 14 of the punch plate when the same is 15 depressed, and said plate 16 at its other end is secured to the punch plate member 12 adjacent to the bend 11 by means of rivets 20. The plate 16, furthermore, is supported at a distance from the member 10 at the 20 bend 11 so as to permit the reception of the cover 2 of the book, and the member 10 normally presses against the plate 16, as indicated in Fig. 3, and therefore acts as a spring clamp upon the cover of the check 25 book when inserted as indicated in Figs. 1 and 2. In addition to the plates thus described, there is provided a stripper plate 18 which is of spring metal and bent into a curved form, as indicated in Fig. 2, one 30 end of the said stripper plate being provided with an aperture 19 which permits the passage of the punch 17 when the presser plate 12 is depressed in the punching operation, and the other end of the stripper plate is 35 secured in position between the plate 16 and the member 12 by means of the aforesaid rivets 20, all of which will be clearly understood by reference to Fig. 2. It will be further observed that the forward end of 40 the stripper plate 18 projects beyond the end 13 of the punch plate 12, so as to provide a guiding surface between the said plates 18 and 13 for the easy insertion of the check and positioning thereof to insure the 45 proper numbers being punched out. It will also be seen that as the member 13 and the stripper plate 18 normally are in close relation, the check is properly guided between them and held close to the aperture 14 in 50 the punch plate; and when the said punch plate is depressed, its pressure upon the check strip clamps it upon the stripper plate 18 to insure the check against shifting when the punching operation in connection with 55 the punch 17 takes place. As soon as the hole is punched, the removal of the pressure upon the punch plate causes it to rise and the stripper plate also rises under its own elasticity and strips the check from the punch. 60 The pressure upon the check is thereby removed and the check may be shifted to position for the punching of the next hole. It will also be seen that as the punching 65 of the paper from the check is done in an upwardly direction, the number to be

punched out may be readily viewed through the aperture 14 for rapid and accurate operation in punching, and moreover, the punched out paper frees itself from the punch mechanism and thereby keeps it in 70 good operative condition.

In utilizing this invention after the check has been filled out in the usual way, it is detached along the line 8 and thereafter is inserted between the end 13 of the punch 75 member 12 and the plate 18 and shifted to the position to bring the numbers of the first column corresponding to the thousands in line with the aperture 14 of the punch plate and thereupon the said plate is depressed 80 to punch out the number corresponding to said thousand designation in the check. If there is no thousand in the amount, then a zero in that column is punched out. Next the check is shifted to bring the right number of the second column under the opening in the punch plate to correspond to the hundred designation in the check and the same is punched as before. This operation is repeated in respect to the tens and the dollars 85 corresponding to the check, said punchings being in the third and fourth columns respectively. It will then be seen that the amount may be read in the normal manner from left to right and should correspond to 90 the amount of the check as drawn. Of course, it will be understood that where the amount of dollars in the check extends only to the digits or to amounts less than the thousand column, such columns as designate 100 the higher values should be punched in their zero marks to prevent raising of the value of the check.

While our invention is specially intended for preventing the raising of checks 105 employed in banking business, we do not restrict ourselves to that particular class of evidences of obligation or payment thereof, as the improvement will apply to any form such as drafts, notes, etc., wherein a specific 110 amount involved is specified and which it is desirable shall not be capable of being raised.

It will now be apparent that we have devised a novel and useful construction which 115 embodies the features of advantage enumerated as desirable, and while we have in the present instance shown and described the preferred embodiment thereof which has been found in practice to give satisfactory 120 and reliable results, it is to be understood that we do not restrict ourselves to the details, as the same are susceptible of modification in various particulars without departing from the spirit or scope of the invention. 125

Having thus described our invention, what we claim as new and desire to secure by Letters Patent is:—

1. A punching means adapted for being secured to the bound volume and comprising 130

- a punch supporting plate and punch attached thereto near one end, a spring stripper plate arranged over the punch and its supporting plate having an opening above the punch and its distant end connected to the punch carrying plate at its end most distant from the punch, and a punch plate above the stripper plate and having at one end a punching aperture in alinement with the punch and its other end also connected with the punch carrying plate at its end most distant from the punch, said punching means provided with a spring clamping plate having one end free and arranged under the punch and its other end connected to the punch carrying plate at its end most distant from the punch, and between which and the punch supporting plate a portion of the bound volume is clamped.
2. In a punching device of the character stated, a sheet plate bent into U shape to provide a clamping plate member and a punch plate member, the latter having a punching aperture, combined with a punch and a supporting plate therefor, said plate at its end most distant from the punch secured to the punch plate member adjacent to its connection with the clamping plate member and providing with said clamping plate member a spring jaw for detachable attachment to a cover of a check or other book, and a spring stripper plate arranged between the punch supporting plate and punch plate member and secured at its end to the latter adjacent to its connection with the punch supporting plate.
3. The invention according to claim 2, wherein further the punch plate member is provided with a depression portion in its upper part adjacent to the punch aperture for receiving the tip of the finger to concentrate the pressure upon the plate in the act of the punching operation.
4. The invention according to claim 2, wherein the stripper plate is curved downward at its free end to contact with the punch supporting plate and form with the end of the punch plate member a receiving jaw for the paper sheet to be positioned between the punch plate member and stripper and be guided thereby above the punch.
5. In a device of the character stated, means for punching a paper sheet comprising plate members in substantially parallel relation and connected at one end to constitute a spring jaw for detachable attachment to the cover of a check book or other holder of checks or the like, one of which plate members is provided with an upwardly extending punch adjacent to its free end, combined with a punch plate member having resiliency and one end united to the first mentioned plate members adjacent to their connected ends and having the other end provided with a punch aperture immediately above the punch, and a spring stripper plate having at one end an opening in alinement with the punch and arranged in yielding relation with the punch plate member and also arranged between said member and the punch and having its free end bent downward away from the punch plate member to provide a guiding channel for receiving the paper to be punched, said stripper plate having its end most distant from its opening secured to the punch plate and punch carrying member adjacent to their connected ends and acting in conjunction with the punch plate member to sustain the paper to be punched clear of the punch and permit of its attachment and positioning by observation through the open aperture of the punch plate member, and wherein further a pressure upon the punch plate member acts to positively clamp the paper upon the stripper plate and thence carrying the paper below the punching edge of the punch while in clamped relation.
6. The invention according to claim 5, wherein further, the downwardly bent end of the stripper plate rests upon the punch carrying plate member, so as to provide an arch shaped plate spring supported at both ends.

In testimony of which invention, we here- 95
unto set our hands.

WILLIAM SAUL SMITH.
FREDERIC SLAYTON WILLIAMS.
